AUTOMATIC BOBBIN DOFFING APPARATUS
James F. King, Jr., and Donald A. Sloan, Winston-Salem,
N.C., assignors to The Bahnsen Company, Winston-
Salem, N.C., a corporation of North Carolina
Filed June 30, 1964, Ser. No. 379,170
20 Claims. (Cl. 57—53)

The present invention relates in general to doffing apparatus for doffing full bobbins from a line of spindles on a textile processing machine, and more particularly to bobbin doffing apparatus to be installed on one end of track rails on a textile spinning machine adjacent a line of spindles thereof which proceeds automatically along the line of spindles to the opposite end of the track and successively doffs full bobbins from the spindles without requiring operator attention.

Heretofore, various mechanisms have been devised to automatically doff full bobbins from a line of spindles on textile spinning machines, in an effort to relieve the labor costs and machine shut-down time incident to the customary manual bobbin doffing procedures. One of the problems encountered in devising a commercially successful automatic doffer has been the imparting of sufficient lift-off force to the bobbin to reliably break the tight frictional bond which develops between the spindle surface and the interior bore surface of the bobbin due to torsional forces occurring during driving of the bobbin by the spindle. Expedients which have been considered effective for insuring such lift-off are the provision of a steady strong lifting force from a rigidly mounted plow member or provision of a sudden strong impact force from a pivoted ejector arm abutting the lower butt of the bobbin. The latter expedient provides certain advantages in compactness of design and motive power requirements, but introduces a considerable problem of properly timing actuation of the ejector arm with arrival in properly aligned relation with the bobbin to be doffed as well as complexity of the mechanism for providing a sufficiently strong, lift-off force. Frequently, rack teeth or projections aligned selectively with the spindles and located on or adjacent one of the track rails on the spinning frame to be engaged by gears, star-wheels, or similar mechanisms and trip the ejector arm have been employed to coordinate actuation of the ejector arm with spindle location. These obviously require high precision customized mechanisms for the spinning frame and doffer and do not insure the desired degree of reliability. Further, special provision must be made to insure holding of the thread until an empty replacement bobbin is fitted on a doffed spindle when warp bobbins are being doffed or in connection with any machine having a doffing procedure wherein no doffer turns are wound on the spindles below the bobbins preparatory to doffing.

An object of the present invention is the provision of novel bobbin doffing apparatus whose operation is controlled by the location of the bobbins on the line of spindles so that variations in spindle spacing can be readily accommodated.

Another object of the present invention is the provision of novel automatic doffing apparatus adapted to track along track rails on a textile processing machine alongside a line of spindles and doff full bobbins therefrom, in which an ejector arm responds to direct physical engagement with each bobbin to imitate an operating cycle wherein the ejector arm imparts a substantially uniform upward propelling force to the bobbins to throw them upwardly off of the spindles.

Another object of the present invention is the provision of novel automatic bobbin doffing apparatus of the type described in the preceding paragraph, wherein the ejector

2

tor arm is moved laterally responsive to direct engagement with the base portions of the successive bobbins to effect loading and sudden release of spring means coupled to the ejector arm to drive it rapidly upwardly with sufficient force to break the friction bond between the bobbins and their spindles and throw the bobbins off of the spindles.

Another object of the present invention is the provision of novel bobbin doffing apparatus of compact design suitable to be mounted alongside separate bobbin doffing apparatus on a transport carriage for convenient transport between spinning frames in a textile spinning room.

Another object of the present invention is the provision of novel bobbin doffing apparatus which can be readily mounted on the spinning frames by use of conventional rectilinear track rails without requiring special modifications to coordinate doffer timing with spindle location.

Another object of the present invention is the provision of novel bobbin doffing apparatus having thread holding means for use with warp bobbins or machines wherein doffing turns are not wound on the spindles preparatory to doffing.

Other objects, advantages, and capabilities of the present invention will become apparent from the following detail description, taken in conjunction with the accompanying drawings illustrating two preferred embodiments of the invention.

In the drawings:

FIGURE 1 is a front elevation view of automatic bobbin doffing apparatus embodying the present invention, illustrated on a wheeled carriage frame;

FIGURE 2 is an enlarged side elevation view thereof to enlarged scale with part of the housing broken away, taken along the line 2—2 of FIGURE 1;

FIGURE 3 is an enlarged vertical section view taken along the line 3—3 of FIGURE 1;

FIGURE 4 is a horizontal section view showing details of the ejector arm and supporting structure therefor, taken along the line 4—4 of FIGURE 3;

FIGURE 5 is a fragmentary rear elevation view of the ejector arm supporting structure, taken along the line 5—5 of FIGURE 3;

FIGURE 6 is a section view showing details of the thread cutter mechanism, taken along the line 6—6 of FIGURE 3.

Referring to the drawings, wherein like reference characters designate the corresponding parts throughout the several figures, the automatic bobbin doffer mechanism of the present invention, designated generally by the reference character 10, is a compact unit occupying relatively small space adapted to be mounted on a generally vertically extending mounting plate 11 in the upper region thereof, preferably supported on a wheeled transport carriage 12 for convenient transportation of the doffer mechanism between the spinning frames in a textile spinning room. The transport carriage 12 and mounting plate 11 are preferably of the construction disclosed more completely in our patent application filed concurrently herewith entitled Transporting Carriage for Automatic Doffing Apparatus and the Like, wherein the mounting plate 11 has a pair of upper track wheels 13 and a single lower track wheel 14 projecting from the surface of the mounting plate 11 toward the spinning frame to be doffed, the mounting plate 11 being adapted to assume a substantially vertical plane upon fitting of the upper track wheels 13, which are preferably peripherally grooved, on an upper horizontal track rail 15 and by lateral engagement of the lower track wheel 14 with the lateral surface of a lower horizontal track rail 16. The track rails 15, 16 would be fixed on the side of the textile

carriage 12.

spinning frame adjacent a line of spindles thereon and arranged in appropriate positions to dispose the mounting plate in a substantially vertical plane. When the track wheels 13, 14 are properly positioned on the rails 15, 16, adjacent one end of the line of spindles, the bobbin doffer and associated carriage are self-propelled along the length of the rails and line of spindles, for example by an electric motor 17, and gear reduction unit if desired, mounted on the rear side of the mounting plate 11, coupled to at least one of the upper track wheels 13 for example by a drive chain or belt 18.

In practice, it is preferred that the mounting plate 11 be sized to also carry an automatic donner unit, indicated diagrammatically at 19, alongside the doffer mechanism 10, in trailing relation thereto relative to the direction of tracking movement along the line of spindles, to automatically place empty bobbins on the spindles from which full bobbins have just been doffed.

The doffer mechanism is supported in a housing frame 20 formed of a pair of rigid side frame members 21, 21' disposed in parallel vertical planes spaced slightly from each other and extending perpendicularly from the rear surface of the mounting plate 11. Between the side frame members 21, 21' is a rigid elongated ejector or lifter arm 22 having a flanged concavely curved outer face 23 adapted to engage the adjacent side and bottom portions of the butt 24 of a fill bobbin 25 disposed on each of the spindles along the line of spindles of the spinning machine, one of which is indicated at 26 in FIGURE 3. The inner end of the ejector arm 22 remote from the spindle positions is pivoted on a horizontal transverse pivot shaft 27 journaled on a mounting plate 28 pivoted for movement about a vertical axis on axially aligned upper and lower vertical pivot shafts 29, 30 extending from the top and bottom thereof. The lower vertical pivot shaft 30 extends through and is journaled in a vertically extending yoke member 31 having the depending legs thereof journaled on a transverse bearing shaft 32, mounted in the side frame members 21, 21'. Vertical lifting movement of the ejector arm 22 is effected by means of a cable 33 anchored to the ejector arm near the outer working end thereof and extending upwardly over a pulley 34 disposed on a pulley shaft mounted on the side frame members 21, 21'. The cable 33 then extends downwardly at the back of the pulley 34 through an end bushing 35, which is freely slideable on the cable, into a vertically reciprocative cylindrical shell 36 and terminates in a flanged end member 37 within the shell 36 having a shoulder formation 38 spaced upwardly from the lower end thereof. A coil spring 39 is disposed within the shell 36 between a flange of the end bushing 35 and the flange of the end member 37, the upper end of the shell 36 being flared inwardly to form an upper limit stop for the end bushing 35 confining the same within the shell 36, and the lower end of the shell 36 being connected by pin 40 to the plunger 41a of solenoid 41.

The solenoid 41 is actuated by a suitable stationary switch 42, preferably of the snap-action type whose location is subsequently described. The solenoid 41 is normally in a deenergized state, wherein its plunger 41a is projected to the position illustrated in FIGURES 2 and 3 limited by a suitable stop member 43, wherein the outer working end of the ejector arm 22 is disposed at an appropriate level to engage a lower side portion, and project slightly under, the bobbin butts 24. Also pivotally supported on the horizontal transverse pivot shaft 27 for the ejector arm 22 is a magnet supporting bracket 44 of generally bell-crank configuration in lateral profile, having an outwardly projecting arm 44a extending substantially parallel to the ejector arm 22 in the normal position of the latter and supporting at the outer end thereof a hold-down magnet 45 located immediately below the ejector arm 22. The hold-down magnet is restrained in the vertical position illustrated in FIGURES 2 and 3 by a strap member 46 connected at one end to

an anchor formation on the bracket 44 adjacent the magnet 45 and at its other end to the mounting plate 11 or other suitable portion of the doffer frame. The bracket 44 also includes depending transversely spaced arms 44b, to the lower ends of which centering coil springs 47 are coupled, the opposite ends of the coil springs 47 being suitably anchored to the doffer frame to continuously urge the associated magnet supporting bracket 44 and ejector arm 22 to a centered position about the vertical axis defined by pivot shafts 29, 30 locating the outer portions of the ejector arm 22 substantially midway between the side frame member 21, 21'. The outermost end portion of the bracket arm 44a is provided with a rearwardly projecting switch actuating flange 44a' disposed laterally of the side frame member 22 in a trailing direction relative to the direction of tracking movement of the doffing unit. The flange 44a' is designed to actuate the snap action switch 42 controlling solenoid 41 and fixed to the frame member 22 adjacent the flange 44a', when the ejector arm 22 is displaced in a trailing direction about the vertical axis through shafts 29, 30. An ejector return spring 48 connected between portions of the magnet supporting bracket 44 and ejector arm 22 spaced outwardly from the pivot shaft 27 therefor biases the ejector arm 22 downwardly into abutment with the upper surface of the magnet 45 when the ejector arm has been lifted from the magnet by the cable 33.

A fixed elastic stop 49 is mounted on the doffer frame at a position above the ejector arm 22 to limit the upward travel of the ejector arm and absorb its kinetic energy.

A receiving chamber 50 is provided in the upper region of the doffer between the side frame members 21, 21' and comprises a front wall 51, an inclined bottom wall 52 and a pair of side walls 53 rigidly secured together, and pivotally hung from a transverse horizontal pivot shaft 54 disposed adjacent the uppermost ends of the side frame members 21, 21'. The receiving chamber 50 has a bobbin receiving opening 55 therein normally closed by a pair of gates 56, preferably formed of nylon, hinged to the opposite lateral edges of the opening 55 and biased to a closed position determined by stop shoulder 57 by spring means such as torsion spring means 58. An anchor 59 is disposed immediately below and carried by the bottom wall 52 of receiving chamber 50 to which one end of a flexible linkage member 60 is fixed, the other end being connected to the upper end portion of the upper vertical pivot shaft 29 and provide a lost motion connection therebetween. The receiving chamber 50 is resiliently biased by spring 61 connected between the bottom 52 and a stationary spring anchor to an outwardly or forwardly projected position, illustrated in FIGURES 2 and 3, wherein the bobbin receiving opening 55 and gates 56 vertically overlie the bobbin and spindle when the doffing mechanism is laterally aligned therewith.

The receiving chamber 50 is selectively retractable about the pivot shaft 54 to a position aligning the front wall 51 thereof with the vertical front edges of the side frame member 21, 21' by means of a solenoid 62 fixed to one of the side frame members near the upper end thereof and having a reciprocative plunger 62a coupled by a pin and slot connection with one or both of the side walls 53 of receiving chamber 50. The solenoid 62 is controlled by a suitable switch, not shown, mounted on the doffer at a position to be engaged and actuated by the end framework of the spinning frame, which usually projects into the path which would be traversed by the front portion of the receiving chamber in the outwardly projected position of FIGURES 2 and 3, to energize the solenoid 62 and withdraw the receiving chamber 50 to its retracted position. This action, through the connection of linkage 60 with upper vertical pivot shaft 29 also swings the yoke member 31 and mounting plate 28 rearwardly about the bearing shaft 32, thereby retracting somewhat the ejector arm 22 and associated mag-

net supporting bracket 44 and magnet 45. The bend in the linkage 60 provides for some lost-motion between the movement of the receiving chamber 50 and shaft 29 to allow for the larger stroke required for retraction of the receiving chamber 50.

In the operation of the above-described mechanism to doff fill bobbins from the spindles of the spinning frame, the mounting plate 11 is coupled on the track rails 15, 16 of the spinning frame in the manner previously described and the manual control switch, fixed for example on one of the side frame members 21, 21' as indicated at 63 in FIGURE 1, is actuated to energize the motor 17 and effect self-propelled movement of the doffing apparatus in the preselected direction of travel, for example to the right as viewed in FIGURE 1. As the doffing apparatus reaches a position alongside the first bobbin 25, the flanged face 23 on the end of the ejector arm 22 engages the bobbin butt 24 in a manner so that the bobbin butt intervals with the path of travel of the apparatus. The force exerted on the outer working end of the ejector unit 22 by the bobbin butt 24 as the apparatus travels alongside the spinning frame rotates the ejector arm 22 slightly about the vertical axis through pivot shafts 29, 30 until the switch actuating flange 44a' depresses the plunger of the normally open switch 42, whereupon the solenoid 41 is energized. Energization of the solenoid 41 effects retraction of its plunger 41a, imparting downward movement to the shell 36 surrounding the spring 39. During initial downward movement of the solenoid plunger 41a and shell 36, the end bushing 35 carried with the upper end of the shell 36 slides downwardly along the cable 32 progressively compressing the spring 39 between the flange of the end bushing 35 and the flange of the end member 37. However, during this initial phase of plunger and shell movement, the ejector arm 22 is restrained in its downward position by the hold-down magnet 45, thereby holding the cable 32 and the cable end member 37 against movement and effecting compression of the spring 39 due to the progressively decreasing distance between the upper end of shell 36 and the end member 37. However, when the end bushing 35 reaches the shoulder formation 38 on the cable end member 37, the remaining pulling force of the solenoid 41 is imparted directly to the cable 32 through the shell 36 and end bushing 35. The shock load of the direct application of force from the solenoid plunger to the cable 32 then occurring and the inertia load built up in the moving parts overcomes the holding capacity of the magnet 45 and, upon initial separation of the ejector arm 22 from contact with the magnet 45, the energy stored in the spring 39 is applied to the ejector arm 22 and bobbin butt 24 substantially instantaneously, effecting such rapid upward propelling force on the bobbin 25 as to throw the bobbin in a free flight or ballistic manner through the opening 55 in the receiving chamber 50. The return force of the torsion springs 58 biasing the hinged gates 56 to closed position is such that the propulsive force of the bobbin readily opens the gates to allow passage of the bobbin therethrough. The bobbin is stopped in its upward flight by the resilient bumper pad 64 located at the top of the chamber 50, whereupon the bobbin falls downwardly and is deflected by the now closed gates 56 and slides down the inclined surface formed by the bottom wall 52 of the chamber 50. The bobbin exits from the rear of the apparatus and is deflected downwardly by a suitable deflecting hood 65 into a storage container, which may, for example, be in the form of an upwardly opening box or receptacle removably supported on a lower portion of the carriage 12.

It will be apparent that as soon as the bobbin is elevated from its spindle into a flight condition by the ejector arm 22, the side load on the ejector arm is relieved, thus relieving the pressure holding the snap action switch 42 in closed position and permitting return of the switch 42, for example by its internal return spring, to open position de-energizing the solenoid 41. The springs 47 then effect

return rotation of the magnet supporting bracket 44 and ejector arm 22 about the vertical axis through shafts 29, 30 to the centered position, while return spring 48 thereupon returns the ejector arm 22 to its normal lower position.

By this arrangement, the operation of the mechanism to energize the solenoid 41 and thereupon successively compress the spring 39 and then release the stored energy in the spring through the cable 33 to the ejector arm 22 is effected responsive to direct engagement of the flanged face 23 of the ejector arm 22 with each bobbin butt 24 so that the coordination of timing of these cycle phases with proper location of the bobbins is assured since the cycle is initiated responsive to direct contact of the ejector arm 22 with the bobbin butt. Further the preloading or compression of the spring 39 achieved prior to application of direct pulling force from the solenoid plunger 41a to the cable through abutment of the bushing 35 with the shoulder formation 38 insures that sufficient force is stored in the spring to disrupt any friction bond which may exist between the spindle and the adjacent internal bore surface of the bobbin, and effect sufficient upward propulsion of the bobbin to insure its passage through the receiving chamber opening 55.

It will be observed from FIGURES 1-3 and 6 that a thread guide 66 is mounted on the receiving chamber 50 near the portion thereof nearest the spinning frame. This thread guide 66 is a smooth tubular member designed to guide the thread that extends from the raised lappets of the spinning frame to the ring travelers under the bobbins. Without this thread guide, the trailing thread may hang on some of the hinge mechanisms for the gates 56 or other associated parts with consequent breakage of the thread, so that manual piecing up would be required when the spinning frame is restarted.

When the above-described mechanism is used to doff fill bobbins or in conjunction with textile processing machines wherein doffing turns of the thread or roving are formed on the spindles below the bobbins as part of the machine shut-down procedure preparatory to doffing, the thread extending from the raised lappet above each spindle and through the ring traveler is anchored to the spindle by the doffing turns so that thread breakage is produced between the doffing turns and the bobbin as the bobbin is tossed upwardly off of the spindle. This insures that breakage will not occur in portions of the thread that would leave a loose thread end extending from the ring traveler which could pull through the ring traveler and require manual piecing up when the spinning frame is restarted after the doff and don cycle. However, complications are introduced when using such apparatus to doff warp bobbins or with machines that do not provide for such doffing turns, as there are no anchoring turns on the spindle and the loose thread end extending from the ring traveler when the thread breaks during bobbin ejection will not start winding on the replacement bobbin upon restarting of the spinning frame.

Accordingly, to provide for reliable thread control in such installations, the doffing unit may be provided with a thread cutting mechanism to sever the thread at a selected location during bobbin doffing and means to hold the thread end until an empty bobbin replacement has been donned on each doffed spindle. To provide these functions, the center of the rear edge of the bobbin entrance opening 55 adjacent the free ends of the gates 56 is notched as indicated at 69, and a thread cutter 70 is located immediately under the bottom wall 52 of the receiving chamber 50, comprising a stationary cutting blade or stator 71 fixed to a suitable mounting bracket 72 secured to the side frame members 21, 21' and having a convergent working end terminating in a V-notch 73 substantially aligned with the notch 69. Both edges of the V-notch 73 are sharpened shearing edges. An oscillating cutter blade 74 has a convergent tip defining sharpened shearing edges and is pivoted at 75 to the

stator blade 71 so that its shearing edges move beneath the stator blade notch 73. A connecting rod 76 extends from an oscillator pin 77 on the oscillating blade 74 to a crank pin 78 of the crank disk 79 on the shaft of an electric motor 80 fixed to one of the side frame members 21, 21'. The lower oscillating cutter blade 74 is continuously urged against the stator blade 71 by a spring 81 bearing on a bracket 81' fixed to the frame members.

Immediately below the cutting mechanism 70 is a horizontal tubular air handling manifold 82 having a forwardly opening narrow orifice 83 therein. The manifold 82 and orifice 83 include an upper horizontal leg substantially spanning the distance between the side frame members 21, 21' having an enlarged portion of the orifice 83 at the center thereof, and a vertical depending leg extending downwardly along the frame member 21 to the vicinity of the base of the spindles when the doffer is in proper location at the side of the spinning frame. A suction pipe 84 extends downward to a convenient location, for example behind the mounting plate 11, and is connected to a suction blower 85 or other suitable suction source.

In the operation of the thread cutting and holding mechanism when doffing warp bobbins or bobbins presenting similar problems, the bobbin thread trails from the bobbin down to the ring traveler in several loose turns about the spindle as the bobbin is thrown upwardly by ejector arm 22 through the hinged gates 56. The spring loaded gates 56, of course, swing open responsive to the impact force of the bobbin and immediately return to their closed horizontal position as soon as the bobbin completely travels through the opening 55 toward the pad 64. The closing of the gates 56 while the bobbin is up in the receiving chamber 50 catches the thread trailing the warp bobbin butt and moves it into the narrow slot formed between the free edges of the gates 56. As the bobbin then falls back onto the closed gates 56 or onto bottom wall 52, the trailing thread drags down the slot between the gates and into the slots 69, 73 of the bottom wall 52 and cutter stator 71, where the thread is cut by the shearing coaction of the oscillating cutter blade 74 and the edges of the V-notch 73 in stator blade 71. When the cutter snips the trailing thread, the loose end of the thread which runs up from the ring traveler is caught in orifice 83 by the suction stream of air, and due to the forward movement of the doffer, the thread is pulled along orifice 83 and can extend in retained condition all the way to the bottom of the orifice. In this way, the loose thread end is held by the manifold suction until an empty replacement bobbin can be installed on the spindle vacated by the doffed bobbin. The replacement empty bobbin jams between the bobbin and spindle the loose thread turns wrapped around the spindle and extending between the ring traveler and the manifold, thereby anchoring the thread end so that proper winding on the spindle occurs when the spinning frame is restarted.

While but two preferred examples of the present invention have been particularly shown and described, it is apparent that various modifications may be made therein within the spirit and scope of the invention, and it is desired, therefore, that only such limitations be placed on the invention as are imposed by the prior art and set forth in the appended claims.

What is claimed is:

1. Apparatus for doffing bobbins from a row of upright spindles on a machine comprising doffing means including a lifter arm movable along the row of spindles into a position engaging each individual bobbin, means supporting said lifter arm for movement relative to the doffer means in a first direction responsive to engagement with the individual spindles and in a second direction effective to lift the bobbins from their spindles, lifter arm driving means for moving the lifter arm rapidly in said second direction from a selected bobbin engaging

position for ejecting the bobbin from the spindle, and means responsive to movement of said lifter arm in said first direction to actuate said driving means for driving the lifter arm in said second direction and eject the engaged bobbin from its associated spindle.

2. Apparatus for doffing bobbins from a row of upright spindles on a machine comprising doffing means including a lifter arm movable along the row of spindles into a position engaging each individual bobbin, means supporting said lifter arm for movement relative to the doffer means in a first direction responsive to engagement with the individual spindles and in a second direction effective to lift the bobbins from their spindles, spring means for driving said lifter arm in said second direction, means for loading said spring means to establish a potential bobbin ejecting force, and means responsive to movement of said lifter arm in said first direction through a selected distance to release potential force from said spring means to said lifter arm for driving the lifter arm in said second direction and eject the engaged bobbin from its associated spindle.

3. Apparatus for doffing bobbins from a row of upright spindles on a machine comprising doffing means including a lifter arm movable along the row of spindles into a position engaging each individual bobbin, means supporting said lifter arm for movement relative to the doffer means in a first direction responsive to engagement with the individual spindles and in a second direction effective to lift the bobbins from their spindles, spring means for driving said lifter arm in said second direction, means for loading said spring means to establish a potential bobbin ejecting force, a hold-down magnet for restraining said lifter arm against movement in said second direction during loading of said spring means, and means responsive to movement of said lifter arm in said first direction through a selected distance to release potential force from said spring means to said lifter arm for driving the lifter arm in said second direction and eject the engaged bobbin from its associated spindle.

4. Apparatus for doffing bobbins from upright spindles on spinning frames and the like comprising a doffing unit arranged to move longitudinally along a line of full bobbins on the spinning frame, said doffing unit including an ejector member having a portion adapted to directly engage the bobbins in succession for lifting them from their respective spindles, means supporting said ejector member for displacement in a selected direction responsive to direct physical engagement with each successive bobbin as the doffing unit moves along said line of bobbins, means for moving the ejector member rapidly from a lower bobbin engaging position to a raised position for ejecting the bobbin from the spindle, and means responsive to displacement of said ejector member in said selected direction to render said last-named means operative to eject the bobbin engaged by the ejector member from its associated spindle.

5. Apparatus for doffing bobbins from a row of upright spindles on a textile machine comprising doffing means arranged to move longitudinally along said row of spindles, said doffing means including an ejector arm having an outer end normally positioned to engage lateral and bottom portions of the lower end of each bobbin, spring means for urging said ejector arm to a raised position, magnet means releasably holding said ejector arm in said normal position against force exerted by the spring means, said ejector arm being movable laterally by engagement of said outer end with each bobbin, and means responsive to each lateral movement of the lifter arm for releasing said lifter arm to be driven by the spring means whereby said ejector element moves rapidly upward to eject the bobbin from the spindle.

6. Apparatus for doffing bobbins from upright spindles on spinning frames and the like comprising a doffing unit arranged to move longitudinally along a line of full bobbins on the spinning frame, said doffing unit including an

elongated lifter arm having an outer end engageable with each individual bobbin and an inner pivot portion pivotally mounted for movement in a vertical plane about a horizontal pivot axis, means supporting said lifter arm adjacent said pivot portion for movement about a vertical pivot axis to permit lateral movement of the lifter arm relative to the doffing unit responsive to direct physical engagement of said outer end with each successive bobbin as the doffing unit moves along said line of bobbins, means for driving said lifter arm rapidly about said horizontal pivot axis from a lower bobbing engaging position to a raised position for ejecting a bobbin engaged by said outer end from its associated spindle, and means responsive to lateral movement of said lifter arm about said vertical pivot axis when said outer end engages a bobbin during relative doffing unit movement to render said last-named means operative to drive the lifter arm upwardly and eject the bobbin engaged thereby from its spindle.

7. Apparatus for doffing bobbins from upright spindles on spinning frames and the like comprising a doffing unit arranged to move longitudinally along a line of full bobbins on the spinning frame, said doffing unit including an elongated lifter arm having an outer end engageable with each individual bobbin and an inner pivot portion pivotally mounted for movement in a vertical plane about a horizontal pivot axis, means supporting said lifter arm adjacent said pivot portion for movement about a vertical pivot axis to permit lateral movement of the lifter arm relative to the doffing unit responsive to direct physical engagement of said outer end with each successive bobbin as the doffing unit moves along said line of bobbins, spring means coupled to said lifter arm for driving the same rapidly upwardly from a lower bobbin engaging position with sufficient force to toss the bobbin upwardly off of its associated spindle, means for loading said spring means to store energy therein, and means responsive to lateral movement of said lifter arm about said vertical pivot axis through a selected distance when said outer end engages a bobbin during relative movement of the doffing unit to apply the stored energy in said spring means to said lifter arm to drive the lifter arm upwardly and toss the bobbin engaged thereby from its spindle.

8. Apparatus for doffing bobbins from upright spindles on spinning frames and the like comprising a doffing unit arranged to move longitudinally along a line of full bobbins on the spinning frame, said doffing unit including an elongated lifter arm having an outer end engageable with each individual bobbin and an inner pivot portion pivotally mounted for movement in a vertical plane about a horizontal pivot axis, means supporting said lifter arm adjacent said pivot portion for movement about a vertical pivot axis to permit lateral movement of the lifter arm relative to the doffing unit responsive to direct physical engagement of said outer end with each successive bobbin as the doffing unit moves along said line of bobbins, spring means coupled to said lifter arm, and actuating means responsive to lateral movement of said lifter arm about said vertical pivot axis through a selected distance for successively loading said spring means to establish a potential bobbin ejecting force and releasing the established force to drive the lifter arm upwardly from a lower bobbin-engaging position and thereby eject the bobbin engaged by said outer end from its spindle.

9. Apparatus for doffing bobbins as defined in claim 8, wherein said actuating means comprises an electrical solenoid having a reciprocative plunger coupled to said spring means, means for loading said spring means to establish said ejecting force during an initial portion of the stroke of said plunger in one direction and then applying said force from said spring means to said lifter arm during the remainder of said stroke, and electrical switch means on said doffing unit actuated responsive to said lateral movement of said lifter arm for energizing said solenoid to move said plunger through said stroke.

10. Apparatus for doffing bobbins as defined in claim

8, wherein said actuating means comprises an electrical solenoid having a reciprocative plunger coupled to said spring means, means for loading said spring means to establish said ejecting force during an initial portion of the stroke of said plunger in one direction and then applying said force from said spring means to said lifter arm during the remainder of said stroke, electrical switch means on said doffing unit actuated responsive to said lateral movement of said lifter arm for energizing said solenoid to move said plunger through said stroke, and a hold-down magnet adjacent said lifter arm for magnetically attracting said lifter arm at said lower position to restrain said lifter arm against upward movement during loading of said spring means.

11. Apparatus for doffing bobbins as defined in claim 8, wherein said spring means comprises a coil spring, a cable extending from said lifter arm through said coil spring and terminating in a cable shoulder member bearing against one end of said coil spring and a loose fitting bushing slidable on the cable bearing against the other end of said spring, said actuating means including a shell loosely encasing said coil spring having shoulder means bearing against said bushing and a solenoid having a plunger coupled to said shell, said solenoid being operative responsive to said lateral movement of said lifter arm to move said shell axially to draw said bushing through a selected spring loading range toward said cable shoulder member to compress said coil spring therebetween until the bushing engages a portion of said shoulder member and then concurrently draw the bushing and shoulder member through a further range, and magnet means for holding said lifter arm against lifting movement during movement of said bushing through said spring loading range, the holding force of said magnet means being overcome by said solenoid when said bushing engages said cable shoulder member to permit release of said coil spring and application of the return force thereof to said lifter arm to rapidly eject the bobbin.

12. Apparatus for doffing bobbins from a row of upright spindles on a machine comprising doffing means including an elongated lifter arm pivoted for movement about a horizontal pivot axis and having an outer end engageable with each individual bobbin, spring means coupled to said lifter arm for rapidly driving the same upwardly from a lower bobbin engaging position, said spring means comprising a coil spring, a cable extending from said lifter arm through said coil spring and terminating in a cable shoulder member bearing against one end of said coil spring and a loose fitting bushing slidable on the cable bearing against the other end of said spring, a shell loosely encasing said coil spring having shoulder means bearing against said bushing and a solenoid having a plunger coupled to said shell, said solenoid being operative to move said shell axially to draw said bushing through a selected spring loading range toward said cable shoulder member to compress said coil spring therebetween until the bushing engages a portion of said shoulder member and then concurrently draw the bushing and shoulder member through a further range, and magnet means for holding said lifter arm against lifting movement during movement of said bushing through said spring loading range, the holding force of said magnet means being overcome by said solenoid when said bushing engages said cable shoulder member to permit release of said coil spring and application of the return force thereof to said lifter arm to rapidly eject the bobbin.

13. Apparatus for doffing bobbins from upright spindles on spinning frames and the like comprising a doffing unit arranged to move longitudinally along a line of full bobbins on the spinning frame, said doffing unit including an elongated lifter arm having an outer end normally projecting to a position to engage lower end portions of each bobbin during movement of the doffing unit along said line of bobbins, means supporting said lifter arm for

movement about a horizontal pivot axis, means for producing a signal upon engagement of said lifter arm with a bobbin, means responsive to said signal for rapidly driving said lifter arm rapidly upwardly about said pivot axis from a lower bobbin engaging position to throw the bobbin engaged thereby upwardly from its spindle when said lifter arm is selectively aligned with each bobbin, and a bobbin receiving chamber supported in said doffing unit above said lifter arm having a bobbin entrance opening positioned in the path of movement of the bobbins thrown upwardly by said lifter arm through which the bobbin enters said chamber, hinged gate members covering said opening to be opened responsive to impact of a thrown bobbin therewith for admitting the bobbin to said chamber, and spring means for returning said gates to closed position immediately following passage of a bobbin upwardly therethrough to prevent downward movement of the bobbin through said opening.

14. Apparatus for doffing bobbins from upright spindles on spinning frames and the like comprising a doffing unit arranged to move longitudinally along a line of full bobbins on the spinning frame, said doffing unit including an elongated lifter arm having an outer end normally projecting to a position to engage lower end portions of each bobbin during movement of the doffer unit along said line of bobbins, means supporting said lifter arm for movement about a horizontal pivot axis, means for producing a signal upon engagement of said lifter arm with a bobbin, means responsive to said signal for rapidly driving said lifter arm rapidly upwardly about said pivot axis from a lower bobbin engaging position to throw the bobbin engaged thereby upwardly from its spindle when said lifter arm is selectively aligned with each bobbin, and a bobbin receiving chamber supported in said doffing unit above said lifter arm having a bobbin entrance opening positioned in the path of movement of the bobbins thrown upwardly by said lifter arm through which the bobbin enters said chamber, hinged gate members covering said opening to be opened responsive to impact of a thrown bobbin therewith for admitting the bobbin to said chamber, and spring means for returning said gates to closed position immediately following passage of a bobbin upwardly therethrough to prevent downward movement of the bobbin through said opening, said chamber having a lower wall bounding said opening defining an inclined bobbin guide surface declining away from the spinning frame for guiding bobbins admitted to the chamber to a selected discharge zone.

15. Apparatus for doffing bobbins as defined in claim 13 wherein said doffing unit includes carriage means adapted to track on track rails along a side of the spring frame adjacent the line of bobbins, rigid frame members, means supporting said chamber for movement from a projected position disposing said opening and adjacent portions of said chamber vertically above a bobbin to be doffed when said lifter arm engages the bobbin to a retracted position spaced laterally of the line of bobbins sufficient to clear end portions of the spinning frame, and means connecting said chamber with said lifter arm for

5 withdrawing the lifter arm from intercepting relation with the bobbins and end portions of the spinning frame when said chamber is withdrawn to said retracted position.

16. Apparatus for doffing bobbins as defined in claim 15, wherein said chamber is suspended from said frame members for movement about a horizontal pivot axis from said projected position to said retracted position, solenoid means having a reciprocative plunger coupled to said chamber for moving the chamber between said projected and retracted positions, and means supporting said lifter arm supporting means for movement about a horizontal pivot axis spaced below the lifter arm and coupled by linkage means with said chamber for withdrawing said lifter arm away from the line of bobbins upon movement of said chamber to retracted position.

17. Apparatus for doffing bobbins as defined in claim 13, wherein said doffing unit includes thread cutter means disposed to cut threads trailing below bobbins thrown through said opening, and thread holding means for holding the lower end of the thread cut by said cutter means for a selected distance of travel of the doffer unit after doffing of each bobbin.

18. Apparatus for doffing bobbins as defined in claim 13, wherein said doffing unit includes thread cutter means disposed immediately below said chamber having driven shearing blade means adjacent said bobbin entrance opening in the path of trailing threads from bobbins thrown into said chamber to cut said trailing threads, and thread holding means for holding the lower end of the thread cut by said cutter means for a selected distance of travel of the doffer unit after doffing of each bobbin.

19. Apparatus for doffing bobbins as defined in claim 13, wherein said doffing unit includes thread cutter means disposed immediately below said chamber having driven shearing blade means adjacent said bobbin entrance opening in the path of trailing threads from bobbins thrown into said chamber to cut said trailing threads, and pneumatic suction thread holding means adjacent said cutting means for holding the lower cut end of each trailing thread cut by said cutting means for a selected period after cutting thereof.

20. Apparatus for doffing bobbins as defined in claim 19, wherein said thread holding means comprises a suction tube having a horizontal leg immediately below said cutter means and a depending leg extending from said horizontal leg along the trailing side of the doffing unit relative to its direction of travel along said line of bobbins, said suction tube legs having a connecting elongated orifice for holding the cut thread end by suction pressure while permitting sliding movement of the thread along said legs.
